US00D677380S

(12) **United States Design Patent**
Julian et al.

(10) **Patent No.:** US D677,380 S
(45) **Date of Patent:** ** Mar. 5, 2013

(54) **AUTOMATIC INJECTION DEVICE**

(75) Inventors: **Joseph F. Julian**, Libertyville, IL (US); **Chuan Li**, Deerfield, IL (US); **Aaron B. Eiger**, Chicago, IL (US); **Mark Kurth**, Beverly Shores, IN (US); **Sabrina Katz**, Chicago, IL (US); **Adam Calif**, Chicago, IL (US)

(73) Assignee: **AbbVie Biotechnology Ltd.**, Hamilton (BM)

(**) Term: **14 Years**

(21) Appl. No.: **29/383,882**

(22) Filed: **Jan. 24, 2011**

(51) **LOC (9) Cl.** 24-02

(52) **U.S. Cl.** D24/113

(58) **Field of Classification Search** D24/112-114, D24/133, 186, 104, 130, 127; 606/181, 185; 604/232, 187, 158, 164.08, 192, 263, 163, 604/181, 184, 198, 227

(57) **CLAIM**

The ornamental design for an automatic injection device, as shown and described.

DESCRIPTION

FIG. 1 is a front perspective view of an automatic injection device with a removable cap on showing the design;

FIG. 2 is a front elevation view thereof;

FIG. 3 is a rear elevation view thereof;

FIG. 4 is a left side elevation view thereof, the right side being a mirror image of the left;

FIG. 5 is a top plan view thereof; and,

FIG. 6 is a bottom plan view thereof.
